[57] **CLAIM**

The ornamental design for a combined vehicle hood shield and windshield deflector, as shown and described.

DESCRIPTION

FIG. 1 is a view in perspective of a combined vehicle hood shield and windshield deflector showing the new design attached to a pick-up truck which is shown in broken lines for illustrative purposes only and is not part of the claimed design;

FIG. 2 is an enlarged right side elevational view thereof; the side opposite that shown being a mirror image;

FIG. 3 is an enlarged top plan view thereof;

FIG. 4 is an enlarged bottom plan view thereof;

FIG. 5 is an enlarged front elevational view thereof; and,

FIG. 6 is an enlarged rear elevational view thereof.

FIG. 1

FIG. 2

FIG. 3
